SAFETY CATCH FOR BAR PINS AND
THE LIKE

Agnes M. La Paglia, Livingston, N. J.

Application March 6, 1943, Serial No. 478,211

1 Claim. (Cl. 24—157)

This invention relates to safety catches for bar pins and the like.

An object of this invention is to provide a highly improved safety catch for a bar pin, or the like, which shall be relatively inexpensive to manufacture, easy to manipulate, smooth and positive in operation and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention,

Fig. 1 is a top plan view of a bar pin with safety catch embodying the invention;

Fig. 2 is a rear elevational view thereof;

Fig. 3 is an enlarged cross-sectional view taken on line 3—3 of Fig. 2;

Fig. 4 is an end view of the structure shown in Fig. 3;

Fig. 5 is a cross-sectional view taken on line 5—5 of Fig. 3;

Fig. 6 is a perspective view of a piece of solder prepared stock from which the piece of the safety catch which is soldered to the bar, is made; and

Fig. 7 is a view similar to Fig. 3 and illustrating a modified construction.

Referring now in detail to the drawing, 10 designates a bar pin provided with a safety catch 11 embodying the invention. The bar pin 10 comprises a bar of plate or ornamental member 12 to one end of which is soldered a hinge 13, to which is hinged the attaching pin 14.

The safety catch 11 which engages the pointed end of pin 14 comprises a member 15 soldered to plate or bar 12.

The piece 15 is formed with a part cylindrical through opening 16 and a constricted opening 17 at one side of said piece and communicable with said part cylindrical opening. Piece 15 may be made from a piece of solder prepared stock 15a which has solder 18 incorporated into a surface thereof.

Rotatably mounted on member 15 is a mem- 50

ber 20, having a part cylindrical, hollow portion 21 rotatably received in opening 16, and forming a slot 22 through which pin 14 is inserted. At one end of wall or portion 21 is an end wall 5 23 having a pair of spaced fingers 24 forming a slot 25 therebetween extending to the center of wall 23. The inner ends of wall 21 is riveted or turned out to keep member 20 from coming out. Fingers 24 serve as a handle for rotating member 20. The pin enters the hollow cavity in member 12. Fig. 5 shows the locked position of the safety catch. To open it handle fingers 24 are rotated 180° to bring slots 22 and 25 in register with opening or slot 17.

In Fig. 7 is shown a safety catch 11a similar to catch 11 except that end wall 23 has a larger slot 25a similar to slot 25, so as to permit the pin 14 to pass therethrough.

It will thus be seen that there is provided a 20 device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

A bar pin comprising a plate, a hinge thereon, a pin hinged thereto, a safety catch for said pin comprising a member soldered to said plate and formed with a part cylindrical opening, and a constricted opening communicating therewith, a member rotatable on said first member including a part cylindrical wall having a slot received in said part cylindrical opening, an end wall at one 35 end of said part cylindrical wall formed with outwardly extending spaced fingers forming a slot therebetween extending to the center of said end wall and communicating with the slot in said part cylindrical wall, the other end of said part cylindrical wall being riveted over the first member at the inner end of the latter to prevent said second member from coming out of said first member, said pin passing through the slot in said end wall.

AGNES M. LA PAGLIA.
